ROLLER SKATE FRAME

Edward M. Jack, Litchfield, Conn., assignor to
 Union Hardware Company, Torrington, Conn.,
 a corporation of Connecticut

Application June 15, 1948, Serial No. 146,971

Term of patent 14 years

(Cl. D34—14)

To all whom it may concern:

Be it known that I, Edward M. Jack, a citizen of the United States of America, residing at Litchfield, county of Litchfield, State of Connecticut, have invented a new, original, and ornamental Design for Roller Skate Frame, of which the following is a specification, reference being had to the accompanying drawing, forming part thereof.

Fig. 1 is a side elevational view of the roller skate frame, showing my new design.

Fig. 2 is a bottom plan view thereof.

Fig. 3 is a left end view thereof.

Fig. 4 is a sectional view thereof taken on line 4—4 in Fig. 1.

Fig. 5 is a fragmentary sectional view thereof taken on line 5—5 in Fig. 1.

The dotted line showing of the wheels is for illustrative purposes only.

I claim:

The ornamental design for a roller skate frame, as shown and described.

EDWARD M. JACK.
